UNITED STATES PATENT OFFICE.

JAMES H. McCALL, OF COLUMBIA, TENNESSEE.

SANITARY APPLIANCE.

SPECIFICATION forming part of Letters Patent No. 790,701, dated May 23, 1905.

Application filed June 13, 1904. Serial No. 212,415.

To all whom it may concern:

Be it known that I, JAMES H. McCALL, a citizen of the United States, residing at Columbia, in the county of Maury and State of Tennessee, have invented new and useful Improvements in Sanitary Appliances, of which the following is a specification.

This invention relates to what I shall, for convenience, term a "sanitary appliance."

10 The device may be used as a privy, and subsequently the fecal and urinal substances deposited thereinto can be readily and wholly consumed by incineration. The appliance, therefore, is in the nature of a combined privy and excrement-incinerating furnace.

It is a matter of common knowledge that the most prolific cause of camp sickness—such as typhoid fever, dysentery, cholera, &c.—is water pollution and the transmission by flies of disease germs to the soldiers' food, both of which are directly traceable to the presence of camp-sinks, which while necessary are a constant menace to the life and health of the camp. It is well known also that the diseases above mentioned are transmitted to the public in general by infected water and flies from feces in privies and the like.

It is the primary object, therefore, of my invention to provide an appliance that is simple and which is of such character that after having been used as a privy the contents thereof can be quickly and effectively wholly incinerated in order to eliminate all possibility of the transmission of germs from the excremental substances. By the use of the apparatus the prevention and dissemination of foul unhealthy odors, always present in the vicinity of a camp, are assured.

While the sanitary appliance constituting the subject-matter of the present application is adapted, primarily, for use in army camps, it may be otherwise employed with slight modifications within the spirit of my invention.

In the drawings accompanying and forming a part of this specification I illustrate clearly one simple arrangement of the appliance, which will be fully set forth in the following description; but I do not limit myself to the showing thus made, for certain variations

may be adopted within the scope of the claims 50 succeeding such description.

Referring to the drawings, Figure 1 is a perspective view of a series of pits and certain parts mounted therein. Fig. 2 is a like view of privy-box, the parts thereof being 55 separated. Fig. 3 is a similar view of excrement-holders. Fig. 4 is a like view of top for flues and stack. Fig. 5 is a longitudinal sectional elevation of complete apparatus. Fig. 6 is a transverse sectional elevation of same. 60 Fig. 7 is a detail showing a portion of the privy-box seat.

That organization embodying my invention illustrated in the accompanying drawings includes a chamber or chambers, representing, 65 but not necessarily consisting of, a pit or pits suitably formed in the earth. I have indicated four of these pits; but this number is not essential, for two of them can be employed. In fact, a single one can be employed, if necessary. 70 However, I prefer to use at least two, so that while one is being utilized for the reception of excremental substances the contents of the other can be burned out, as will hereinafter appear. The pits are each designated by 5, 75 and they radiate from a central point, although their inner ends are separated. The outer ends or entrances of the pits are made wide in order that fuel can be introduced thereinto to bring about the incineration of 80 the contents thereof. The inner ends of the pits 5 are connected by passages 6, shallower than the flues, and which passages intersect each other and serve as flues, for a purpose that will hereinafter appear. These passages 85 are formed in the earth.

Resting on the surface of the earth and covering wholly the crossing passages or flues 6 is a sheet or plate 7 of metal, to which is detachably connected a vertical stack, as 8. 90 The stack rises centrally from the plate, and its entering end registers with the place of intersection of the two intersecting passages or flues 6. The plate is securely maintained in place by the guy-wires 8' of the stack 8. It 95 will be understood that the opposite ends of each of these passages or flues open into or connect with the inner ends of oppositely-

disposed pits 5. In the opposite walls of each pit or chamber 5 eyebolts, as 9, may be driven, there being four bolts represented in each pit and arranged in horizontally-aligned pairs. The eyes of the bolts constitute bearings for the parallel bars 10, extending longitudinally of the respective pits and constituting supports for the plates 11. Two plates are represented in each pit, although this is not essential, for the number may be increased, or one may be employed, if desired or expedient. Upon the plates 11 fecal matter is deposited, as will hereinafter appear. It will be understood that the horizontal plates 11 are situated above the bottoms of the respective pits, whereby fuel can be placed under the same. Near the head end of each pit is a basin or receptacle, as 12, intended for the reception of urine. This basin, like the other parts within the pit, is made of metal and of such a one as will best withstand the heat generated within the pits during the burning out of the matter within the same. The basins are shown as of substantially rectangular form; but this shape is not material, and their end walls are shown as perforated to receive the eyes of bolts or spikes, as 13, driven into the opposite walls of the several pits about on a line with the bolts or spikes 9. Extending across the tops of the several pits are bars 14, situated a suitable distance apart and held firmly in place in any desirable way. For example, the ends of the bars may be sunk a short distance into the earth. In this way the privy-boxes can rest solidly on the surface of the earth. These bars 14 constitute supports for the bodies 15 of the privy-boxes, the area of the respective boxes being substantially equal to that of the respective pits. The bodies of the privy-boxes preferably are hinged at their corners in order that they can be readily collapsed for convenience of transportation.

The seats of the privy-boxes are denoted by 16, and they are removably associated with the respective bodies 15 and have a suitable number of holes vertically aligned with the plates 11. Said seats are shown as having pendent continuous flanges 16^b to closely hug the bodies. The covers 16^a for the privy-holes are provided with spring-hinges of some suitable kind, the springs of the hinges serving to automatically close the covers and normally to keep the same positively down and in position to close their coöperating holes, thereby to prevent the entrance of flies into the boxes or the escape of odors through said holes.

The bodies of the privy-boxes are made of some suitable metal, and to their outer end walls are hingedly and detachably connected the depending plates 17, which when down effectually close the outer ends of the several pits to prevent flies entering the pits at such places and also the escape of odors.

Each privy-box is provided with a urinal, as 18, which is shown as a funnel vertically aligned with a basin 12, so that the liquid delivered into a urinal will flow therefrom into the basin below the same.

When the plates 11 and basin 12, constituting convenient holders for the excremental matter, of any one of the pits are filled with excremental matter, the latter should be incinerated, and this can be readily and quickly accomplished, without possibility of spreading germs or the dissemination of odors, by building a fire under said plates 11 and basin 12. The incineration of the contents of any one pit can be secured without removal of the privy-box body 15 from the same. During such incineration I cover the pit with a metallic plate, as 19. When the plates and urinal-basin of a pit are filled with excremental matter and it becomes necessary to incinerate the latter, the seat 16 of the box is first removed, after which a plate 19 is dropped into the box-body until it falls upon the cross-bars 14, which serve as a convenient support therefor, at which time it will be apparent that the pit or chamber containing the excrement is wholly inclosed, except, of course, for the flue for the products of combustion leading from the inner end thereof. By placing fuel of a suitable quantity into the combustion-space under the plates 11 and basin 12 and igniting the same the contents of the pit will be incinerated. Access may be had to the pit for the charging of the fuel thereinto by lifting the hinged door or plate 17. The products of combustion arising from the incineration of the matter in the pit pass therefrom into an offtake or flue 6 and from the latter to the atmosphere by way of the stack or pipe 8. The stack 8, it will be evident, is common to several pits or chambers 5. When the mass in any pit has been wholly consumed by fire, the plate or top cover 19 for the pit is lifted from off the cross-bars 14 and the seat for the privy-box over said pit is put into place, when the privy is ready for use.

The body of each privy is collapsible, and the parts associated therewith are removably mounted in place to facilitate the transportation of the same.

By slight changes the appliance can be adapted thoroughly to domestic purposes.

Having thus described my invention, what I claim is—

1. A sanitary appliance involving a combustion-chamber, a collapsible privy-box removably supported above the chamber and provided with means for closing one end of said chamber, means independent of the privy-box for supporting a cover for the chamber, and excrement-catching means in said chamber.

2. A sanitary appliance involving a pit formed in the ground and a fecal-holding plate and a urine-receiving basin supported in the

pit above the bottom thereof, combined with a cover for said pit and a hinged door for closing one end of the pit, the other end thereof having an offtake-flue.

- 5 3. A sanitary appliance involving a pit formed in the ground, eyebolts driven into the opposite walls of the pit above the bottom thereof, bars supported by the eyes of said bolts, plates for holding feces, carried by said 10 bars, a urinal receiving-basin, and eyebolts driven into said walls substantially in line with said plates and constituting a means for supporting said basin.

4. A sanitary appliance involving a pit 15 formed in the ground, and a flue leading from the pit, a plate for covering said flue, having a stack, means in the pit above the bottom thereof for holding excremental matter, and a box-like part supported over the pit having 20 a depending hinged door closing one end of said pit.

5. A sanitary appliance involving a chamber and an offtake-flue leading therefrom, both formed in the ground, means above the bottom 25 of the chamber for catching excremental matter, a box-like part supported over the chamber provided with a removable top having a privy-hole, and a door for closing said chamber.

- 30 6. A sanitary appliance involving a chamber and an offtake-flue leading therefrom, both

formed in the ground, means above the bottom of said chamber for catching excremental matter, cross-bars extending across the pit above the excremental catching means, a box-like part supported by said bars and provided with a removable top having a privy-hole, said bars serving as a support for a cover for said chamber, and a door for closing said chamber.

35

40

7. A sanitary appliance involving a combustion-chamber, a privy-box supported above the chamber and provided with means for closing one end of the chamber and with a removable cover, means independent of the 45 privy-box for supporting a cover for the chamber, and excrement-catching means in said chamber.

8. A sanitary appliance involving a combustion-chamber, excrement-catching means 50 in said chamber, a privy-box having a removable cover, a door for closing one end of said chamber, and means for supporting the privy-box over said chamber and also arranged for supporting a cover for said chamber.

55

In testimony whereof I have hereunto set my hand in presence of two subscribing witnesses.

JAMES H. McCALL.
